Application October 3, 1930. Serial No. 486,131

12 Claims. (Cl. 90—38)

This invention relates to improvements in portable shapers and more particularly to hand operated portable tools for chamfering railway rail ends.

5 The rolling and pounding action of rolling stock in passing along the tops of railway rails tends to elongate the tread portion. This causes a burr to curl over the ends of the rails at each joint. When the rails expand under sun temperature the ends abut one another. As the rolling stock approaches the end of one rail, that end is depressed below the level of the end of the next rail. If the opposing burrs overlap, one or both of them are eventually dislodged by the 10 rise and fall of the rails under the weight of traffic.

The elongation of the rail tread tends to harden it and causes it to stratify longitudinally and become flaky. When these burrs are dislodged, as 15 stated, they pry up a portion of the contiguous tread and remove the top or tread portion contiguous to the rail end. The succeeding passages of the rolling stock cause the wheel tires to pound into these depressions, causing a traction 20 wave to form in the rail tread which eventually crystallizes the whole end of the rail, causing it to check and fracture, rendering it unsafe or impractical for traffic.

This condition is overcome by transversely 25 chamfering the adjacent rail ends to form a notch in the continuity in the rail tread surface, thus removing in advance the portions of the rail ends that would eventually form the substance of the said burrs.

30 It is among the objects of this invention to provide simple and efficient means for chamfering rail ends in railways.

Another object is to provide means for varying the chamfer with respect to the contour of the 35 rail tread.

Another object is to eliminate from the structure slide ways and other mechanisms requiring precision in machine work, and that are unsuited to the working conditions and relatively unskilled handling incidental to track work.

In this specification and the accompanying drawings the invention is disclosed in its preferred form. But it is to be understood that it may be embodied in other forms. It is also to 50 be understood that in and by the claims following the description it is desired to cover the invention in whatsoever form it may be embodied.

In the accompanying three sheets of drawings:

55 Fig. 1 is a diagrammatic side elevation of a

manually operated shaper constructed in accordance with this invention.

Fig. 2 is a plan view from above of the same.

Fig. 3 is an enlarged side elevation of the shaper head assembly.

Figs. 4 to 10 are schematic diagrams illustrating the application of modified leverage actions to accomplish the chamfering or cutting operations from rectilinear to modified contours (see dotted lines) in meeting working conditions within the purview of this invention in the practice of the same.

Fig. 11 is a side elevation of a rail end notched in accordance with this invention.

In Fig. 4 the levers A—B and D—E are shown 70 of equal length and pivotally connected to the tool member B—D. The points A and E are pivotally connected to the frame of the machine, the distance A—E being made equal to

$$\sqrt{BD^2 + (2AB)^2}.$$

Under these conditions, if the cutting point of the tool is at the center of the member and in the line B—D, the tool point will traverse substantially a straight line P—Q as the lever D—E is oscillated thru a small angle Θ . For example, if the levers A—B and D—E are each made 4 inches long and the member B—D is made 12 inches long, the point of the tool will not depart more than .002 inch from a straight line 80 during a stroke of 3 inches, corresponding to $\Theta=45^\circ$.

In Fig. 5 the construction is the same as in Fig. 4 except that the cutting point of the tool, while still in the line B—D, is no longer at the center thereof but instead is nearer to the point B. Under these conditions the trace of the stroke, P—C—Q, will conform substantially to the arc of a circle. For example, if all the dimensions are taken the same as in Fig. 4 except that the distance B—C is 4.4 inches instead of 6 inches, the curve P—C—Q will follow the arc of a circle of 14 inches radius, corresponding to the radius to which the tread of the rail is customarily rolled.

In Fig. 6 the construction is the same as in Fig. 4 except that the arm D—E is made longer than the arm A—B. Under these conditions the trace of the stroke P—C—Q will be part of the arc of a circle. For example, if all the dimensions are taken the same as in Fig. 1 except that the distance A—B is made 3 inches and the distance D—E, 4½ inches, the curve P—C—Q will again follow the arc of a circle of 14 inches radius,

The construction of Fig. 6 is similar to that of Fig. 5 except that the position of the frame pivot A is adjustable to the position A'. Under these conditions the trace of the stroke will be tilted 5 from the position P—C—Q to the position P'—C—Q'. For example, if all the dimensions are taken the same as in Fig. 6 the trace of the stroke will be tilted, when A' is $\frac{1}{2}$ inch to the left of A, at an angle of approximately 5° , corresponding to a rail tread worn down $\frac{1}{4}$ inch on one side.

In Fig. 7 one means of raising and lowering the tool is illustrated. Here the member B—D is formed with a cross-head permitting it to be 15 adjusted from the position B—D to the position B'—D by means of a screw. The trace of the tool stroke is thus adjustable between the limits of P—C—Q and P'—C—Q'.

The construction in Fig. 8 is similar to that 20 shown in the preceding figures but with the addition of a tool carrying member C—F. This construction assures that the angle of the tool with respect to the trace of the stroke will remain substantially constant. The same result 25 will be attained by making the member B—D in Fig. 8 sufficiently long but in general neither method will be required except for the most exacting purposes, since the total change in tool angle with the construction and dimensions of 30 Fig. 5 will not exceed about 8° .

In the construction shown in Fig. 10 the same result is achieved as in Fig. 9. Here the points C and C' trace strokes of the shape desired and are connected, thru a link C—C'—C'. The 35 point C in the member C—C' will thus trace a similar curve and the cutting angle of the tool with respect to its stroke will not vary during the stroke.

In detail the construction illustrated in the 40 drawings, see Fig. 1, comprises the gage frame composed of the side bars 1—1, adapted to extend across the width of the railway track and rest upon the tops of the rails X—X. These bars are joined at their outer ends by the transverse plate 2, which is preferably insulated from the members 1—1 so as not to interfere with the operation of the rail signal circuit. Their inner ends are bolted to the side plates 3—3 which are properly trussed together by the transverse 45 shouldered bolts 4—4 and 5 to form a rigid head. These side plates 3—3 are preferably of cast steel and have the lugs 6 formed thereon and adapted to engage the outer edge of the head of the rail X.

The T shaped clamp has the shaft 7 pivoted in the stirrups 8—8, fixed to the underside of the bars 1—1. The arms 9—9 are fixed to opposite ends of the shaft 7 and are adapted to engage under the head of the rail X. The shaft 7 50 may be made of sufficient length so that the members 9—9 clamp the rail outside of the space occupied by the angle bars. The treadle arms 10—10 are fixed to the shaft 7 on opposite sides of the bars 1—1 and extend above the level of the same, where they are joined by the transverse treadle 11. The treadle clamp assembly is very easily formed into an integral unit by welding the various parts together. When the treadle 55 11 is depressed by the foot of the operator, standing on the platform 12, the clamps 9 rise beneath the head of the rail and clamp it between the clamps 9—9 and the ends of the bars 1—1. This holds the operating head 3—3 rigidly in position 60 on the rail, vertically, laterally, and horizon-

tally—through the bars 1—1, so long as the treadle 11 is depressed.

The cutter bar 13 is preferably yoke shaped for lateral stability. It is actuated from the rear by the handle 14, transversely fulcrumed on the 65 bolt 15 extending between the side plates 3—3, and terminating in the hand grip 14' above the level of the treadle 11. The lower end 16 of the handle is pivoted at 17 to the rear end of the cutter bar. The front end of this bar is pivoted at 18 to the link 19, which in turn is pivoted at 20 to the bell crank lever 21, fulcrumed on the transverse bolt 5, see Fig. 3. The cutter bar thus floats on two links 16—19 between the pivots 15—17—18—20.

The front end of the cutter bar is vertically adjustable by locating the pivot 18 in the cross head 22, slideable in the guides 23, formed on the end of the cutter bar 13. This cross head has the spindle 24 threaded in the nut 25 rotatable 95 above the cross head 22 by means of the counterbalanced handle 26 fixed on the nut 25.

The cutting tool 27 is fixed in the cutter bar intermediate its ends. Its location is determined by the nature of the contour curve it is desired 100 to cut, see descriptions of Figs. 4 to 10. Swinging the bell crank lever 21 vertically, controls the horizontal distance between the pivots 17—20 and so modifies the angle of inclination of the cutting stroke with respect to the frame (or rail). 105 The cross head feed 22—25 determines the depth of the cut made by the tool 27 by raising and lowering the bar 13. If the rail ends are properly aligned, the opposing top corners may be cut away simultaneously, as in Fig. 11, by grinding 110 the cutting nose of the tool 27 to engage both edges. If they are not so aligned each rail end can be chamfered separately.

It has been the practice heretofore to notch 115 these rail ends perpendicularly to their tread planes with a square notch, or with a plane oblique to the tread plane forming a V shape notch at each joint. These angular forms are objectionable since the angles of incidence of the notch with the plane of the rail treads, 120 whether obtuse or acute, center the impact of the wheels on these angles, which, being points, concentrate the crushing stress at the tread portion and tend to disrupt or flake the same, as previously described. Therefore, I recommend 125 the rounded or curved chamfer shown in Fig. 11, in which the impact is absorbed on an arc and distributed throughout a greater area of the rail end, with obviously improved results, as set 130 forth in my copending application for patent of even date, entitled Railway rail joints.

It has also been the practice heretofore to 135 form such square or oblique notches with a manually controlled tool such as a hand grinder. The operator in such cases forms a notch of substantially uniform depth, conforming to the curvature of the rail tread. However, so far as I am aware, no tool for this purpose has been developed up to this time for mechanically guiding the traverse of the tool in a curved line. Such machines as have been proposed have been provided with rectilinear guiding surfaces and have therefore cut a notch deeper at or near the center of the rail tread than at the edges. 140 This is a disadvantage because more material must be removed in order to get sufficient depth at the edges and, particularly in the case of a V-notch, because the notch is wider at or near 145 the center. 150

the center of the tread than would otherwise be necessary.

It is also obvious that the tool point or cutter 27 may be replaced by a milling cutter or abrasive wheel without deviating from the spirit of this invention.

Further, all machines heretofore proposed for rail notching have been provided with either a screw type clamp or with a clamp requiring springs or their equivalent for release. This is a serious disadvantage when a train approaches since in fog or where vision is obstructed, as in the neighborhood of curves in cuts the train may approach dangerously near the operator before he is aware of his danger. If he is required to perform any mechanical act, no matter how simple, before he can release the tool from the rail the danger is greatly increased and particularly in emergency he may leave the apparatus on the track, thus endangering the approaching train as well. I have, therefore, provided a clamp on my machine which is so constructed that when the operator lifts the tool from the track the clamp is thereby automatically freed without possibility of catching or sticking. Although the construction employed is simple in the extreme and may seem almost self evident, its value to tools of this class is out of all proportion to this simplicity and greatly enhances the value 30 of the tool for railway use.

A conventional motor grinding wheel may be substituted for the cutting tool 27.

The operator clamps the machine to the rail end to be chamfered, with the clamps 9—9 at opposite ends of the joint plates Z of the track, so that the cutter 27 engages one or both contiguous rail ends X'—X''. The operator then stands on the platform 12, his weight adding stability to the machine. With one foot on the clamp treadle 40 11, he then reciprocates the handle 14 and adjusts the bell crank 21, and screws down the handle 26 to feed the cutter downward to cut the adjusted contour of chamfer. When the operation is completed, the operator grasps the 45 treadle 11 and lifts the machine free of the track.

The cutter 27 may be automatically fed downward by means of the ratchet 28, encircling and fixed concentrically to the nut 25. This ratchet 50 is engaged by the pawl 29 pivoted axially on the nut 25, and operated by the push rod 30, the end of which is pivoted on any convenient part of the stationary head 3—3 as at 31. This feed is similar to that common on drill presses.

It is manifest that a prime mover may be geared to the operating handle 14 or otherwise connected to reciprocate the cutter bar 13, without departing from the spirit of this invention.

Having thus described this invention what I claim and desire to secure by Letters Patent is:

1. A shaper comprising a frame, a cutter bar, a link extending downward from one end of said cutter bar to said frame, a second link extending upward from the other end of said cutter bar to said frame, and means for swinging said cutter bar on said links.

2. A shaper for slotting rails comprising a frame, means for securing said frame to the rail to be slotted, a cutter bar, a link extending downward from one end of said cutter bar to said frame, a second link extending upward from the other end of said cutter bar to said frame, and means for swinging said cutter bar on said links.

3. A shaper for slotting rails comprising a frame, means for securing said frame to the rail

to be slotted, a cutter bar, a link extending downward from one end of said cutter bar to said frame, a second link extending upward from the other end of said cutter bar to said frame, and means connected to said second link for reciprocating said cutter bar.

4. A shaper for slotting rails comprising a frame, means for securing said frame to the rail to be slotted, a cutter bar, a link extending downward from one end of said cutter bar to said frame, a second link extending upward from the other end of said cutter bar to said frame, means for varying the point of connection of one of said links with respect to said frame, and means for swinging said cutter bar on said links.

5. A shaper for slotting rails comprising a frame, means for securing said frame to the rail to be slotted, a cutter bar, a link extending downward from one end of said cutter bar to said frame, a second link extending upward from the other end of said cutter bar to said frame, independent means for varying the points of connection of one of said links with said cutter bar and said frame, and means for swinging said cutter bar on said links.

6. A shaper for slotting rails comprising a frame, means for securing said frame to the rail to be slotted including a clamp arm pivotally supported beneath said frame and adapted to engage the under side of the ball of said rail, and means connected to said arm for applying pressure thereto, a cutter bar, a link extending downward from one end of said cutter bar to said frame, a second link extending upward from the other end of said cutter bar to said frame, and means for swinging said cutter bar on said links.

7. A shaper for slotting rails comprising a frame, means for securing said frame to the rail to be slotted, a cutter bar, a link extending downward from one end of said cutter bar, a bell crank connecting said link and said frame for varying the path of travel of said cutter bar, a second link extending upward from the other end of said cutter bar to said frame, and means for swinging said cutter bar on said links.

8. A shaper for slotting rails comprising a frame, means for securing said frame to the rail to be slotted, a cutter bar, means for varying the vertical adjustment of said cutter bar, a link extending downward from one end of said cutter bar to said frame, a second link extending upward from the other end of said cutter bar to said frame, and means for swinging said cutter bar on said links.

9. A shaper for slotting rails comprising a frame, means for securing said frame to the rail to be slotted, a cutter bar, a link extending downward from one end of said cutter bar and pivotally connecting said cutter bar and said frame, a second link extending upward from the other end of said cutter bar to said frame, and means for swinging said cutter bar on said links.

10. A shaper for slotting rails comprising a frame, means for securing said frame to the rail to be slotted, a cutter bar, a link extending downward from one end of said cutter bar and pivotally connecting said cutter bar and said frame, a second link extending upward from the other end of said cutter bar to said frame and pivotally connecting said cutter bar and said frame, and means for swinging said cutter bar on said links.

11. A shaper for slotting rails comprising a frame, means for securing said frame to the rail to be slotted, a cutter bar, a link extending down-

ward from one end of said cutter bar and pivotally connecting said cutter bar and said frame, means for varying the position of the pivotal connection between said link and said frame to alter 5 the path of reciprocation of said cutter bar, a second link extending upward from the other end of said cutter bar to said frame, and means for swinging said cutter bar on said links.

12. A shaper for slotting rails comprising a 10 frame having a portion thereof overlying the top

of the rail to be slotted and an arm extending below the level of the top of said rail, a cutter bar, a link pivotally connecting one end of said cutter bar with said arm, a second link extending upward from the other end of said cutter bar to said frame, and operating means connected to said second link for reciprocating said cutter bar.
